UNITED STATES PATENT OFFICE.

JOHN D. AUSTIN, OF TAMPA, FLORIDA.

CLOTHES-WASHER.

1,160,361.

Specification of Letters Patent. Patented Nov. 16, 1915.

Application filed August 31, 1914. Serial No. 859,524.

To all whom it may concern:

Be it known that I, JOHN D. AUSTIN, a citizen of the United States, residing at Tampa, in the county of Hillsboro and State 5 of Florida, have invented a new and useful Clothes-Washer, of which the following is a specification.

The present invention appertains to clothes washers or boilers, and aims to provide a clothes boiler having unique means disposed therein whereby the boiling water and steam will be utilized to thoroughly agitate the clothes for effectively cleaning them.

15 It is also within the scope of this invention to provide a clothes washer of comparatively simple and inexpensive construction, and which will be convenient, practical, serviceable and efficient in its use.

20 With the above and other objects in view which will appear as the description proceeds, the invention resides in the combination and arrangement of parts and in the details of construction, hereinafter described 25 and claimed, it being understood that changes in the precise embodiment of the invention herein disclosed can be made within the scope of what is claimed without departing from the spirit of the invention.

30 The invention has been illustrated in the accompanying drawing, wherein:—

Figure 1 is a vertical section of one form of the invention. Fig. 2 is a horizontal section taken on the line 2—2 of Fig. 1. Fig. 35 3 is a horizontal section of a second form of the invention. Fig. 4 is a vertical section of the variation illustrated in Fig. 3. Fig. 5 is a longitudinal section of the variation. Fig. 6 is a perspective view of the 40 inner member of the variation.

Referring specifically to Figs. 1 and 2, there is illustrated an ordinary circular boiler 1 having a suitable cover 2. In carrying out the present invention, a hood or bell 45 3 is disposed snugly within the lower portion of the boiler 1, the hood or bell 3 being of circular contour, and having the conical top 4. The rim of the hood is arranged parallel with and close adjacent the walls of 50 the boiler and is seated on the bottom thereof. The rim or apron 5 of the hood or bell 3 is provided with a series of lower notches 6, while the top 4 is provided with a central opening 7. Otherwise, the hood or bell 55 3 is imperforate. The hood or bell 3 is provided with a central upstanding nozzle

or spout 8 which has its lower end secured rigidly to the central portion of the bell or hood 4 to communicate through the opening 7, the upper end of the nozzle or spout 8 being closed, and the said nozzle or spout having a vertical series of diametrically opposite outlet apertures 9 extending from the hood to the upper end of the nozzle. The apertures 9 are arranged in pairs, and the apertures of each pair are in alinement diametrically of the spout or nozzle 8, the apertures being arranged at the various sides of the spout or nozzle to properly distribute the water and steam. 70

In use, sufficient wash water is poured within the boiler 1, to cover the hood or bell 3, which forms the generator, and the clothes are placed within the boiler 1 around the upstanding nozzle or spout 8. Then, 75 the boiler 1 is heated from below in any suitable manner, such as, by placing the boiler upon a stove, and the water below the hood or bell 3 will thus become heated, and in boiling will cause the water and steam 80 to be forcibly raised and expelled upwardly into the spout or nozzle 8, and thence radial outward through the apertures 9 to agitate and clean the clothes thoroughly. The water and steam will squirt in all directions 85 from the nozzle or spout 8 from the center of the boiler toward the periphery thereof, and as the water cools at the periphery of the boiler, it will descend and work its way downwardly between the rim 5 of the hood 90 or bell 3 and the periphery of the boiler 1, and thence through the notches 6 back into the hood or bell. Thus, as the water boils below or within the hood or bell 3, it will be forced violently upward within the spout 95 or nozzle 8 with the steam, and will be ejected through the apertures 9 for cleaning the clothes and to establish a continuous circulation of water from the hood 4 up through the nozzle 8 and thence radially and downward around the rim of the hood 3 and back into the hood through the notches 6. The clothes will thereby be thoroughly agitated, and the water or steam passing through the 100 clothes will serve to cleanse the same quickly 105 and thoroughly.

In some instances it may be desired to close some of the apertures 9, for example, when it is not desired to have the water and steam discharged through the upper portion of the circular nozzle or spout 8. In this event, plug bolts 10 are engaged through

the respective pairs of apertures 9, and have nuts 11 threaded thereon to retain them in place, whereby the corresponding apertures will be stopped up or closed to prevent the discharge of water and steam therethrough. 5 The discharge of water and steam is then confined to the other apertures 9. It is understood that if preferable, the plug bolts 10 need not be employed, although they may be desirable under some circumstances. 10 In the variation illustrated in Figs. 3 and 4, the boiler 1' is elongated or elliptical in form, which is also true of its cover or lid 2'. The hood or bell 3' is also elliptical to fit snugly within the boiler 1', and the top 15 4' of the hood or bell 3' is inclined from the sides of the hood to the center or median line thereof. The rim or apron 5' of the hood 3' is provided with the series of notches 6' in its lower edge, to enable the water to return into the hood from the sides of the boiler, and the central or median portion of the top 4' of the hood is provided with an elongated opening or slot 7'. An elongated or relatively flat nozzle or spout 8' has its lower edges secured to the central or median portion of the top 4' of the hood 2' over the opening or slot 7', the sides and ends of the nozzle 8' being inclined, and the 20 sides being provided with opposite apertures 9' which are in alinement. 25 30

The operation of the modified form is practically the same as the form illustrated in Figs. 1 and 2, and need not be reiterated, 35 it being noted that water and steam will be forced upwardly into the spout or nozzle 8' and thence through the outlet apertures 9' into the opposite sides for cleaning and agitating the clothes. The apertures 9' may 40 also be closed by plug bolts 10' engaged through the respective pairs of apertures 9', nuts 11' being threaded upon the bolts

10' to hold them in place and to assist in closing the apertures. It will be obvious, therefore, that the hood or bell and its 45 nozzle or spout may be of various formations. It is of importance that the hood be imperforate with the exception of the upper central opening and the notches in the lower edge of the rim, whereby the boiling 50 water and steam will be forced upwardly into the spout or nozzle which is perforated to enable the water and steam to squirt or spray therefrom. Whichever form is used, it will be remembered that the cardinal 55 point of merit in the use of the invention, resides in the establishing of currents of steam and hot water outwardly through the clothes, unhindered by any counteraction or opposing current. 60

Having thus described the invention, what is claimed as new is:—

In a clothes washer, a boiler, a hood fitting within the lower portion thereof, the top of the hood having a central opening and the rim of the hood having notches in its lower edge, the hood being otherwise imperforate, an upstanding nozzle secured to the center of the hood and communicating through the said opening, the nozzle having opposite alining outlet apertures throughout its length, plug bolts insertible through various respective pairs of apertures for closing the same, and nuts adapted to be threaded onto the plug bolts to retain them 75 in place.

In testimony that I claim the foregoing as my own, I have hereto affixed my signature in the presence of two witnesses.

JOHN D. AUSTIN.
